(57) CLAIM

The ornamental design for a fire pit, as shown and described.

DESCRIPTION

FIG. 1 is a front/left perspective view of a fire pit according to my new design, wherein the fire pit is in a fully-closed configuration;

FIG. 2 is a front view thereof;

FIG. 3 is a rear view thereof;

FIG. 4 is a top view thereof;

FIG. 5 is a bottom view thereof;

FIG. 6 is a left-side view thereof;

FIG. 7 is a right-side view thereof;

FIG. 8 is a front/left perspective view of the fire pit of FIGS. 1 to 7 but wherein the fire pit is in a fully open configuration;

FIG. 9 is a front view thereof;

FIG. 10 is a rear view thereof;

FIG. 11 is a top view thereof;

FIG. 12 is a bottom view thereof;

FIG. 13 is a left-side view thereof; and,

FIG. 14 is a right-side view thereof.

The broken lines in the drawing depict portions of the fire pit that form no portion of the claimed design.
